Inventor:
Irene E. Kelly
By L. L. Bragg Atty.

UNITED STATES PATENT OFFICE.

IRENE E. KELLY, OF HIGHLAND PARK, ILLINOIS.

COMBINATION UNDERGARMENT FOR STOUT WOMEN.

Application filed February 8, 1922. Serial No. 535,081.

To all whom it may concern:

Be it known that I, IRENE E. KELLY, a citizen of the United States, residing at Highland Park, in the county of Lake and State of Illinois, have invented a certain new and useful Improvement in Combination Undergarments for Stout Women, of which the following is a full, clear, concise, and exact description.

10 My invention relates to those undergarments for women that have the general form of chemises and in which crotch pieces join the fronts and backs of the garments at the bottoms thereof. When such a garment is worn by a stout woman it is apt to become uncomfortable when the wearer assumes a stooping or sitting posture and is also liable to be torn when such a posture is assumed.

In order to overcome these disadvantages 20 I form the back of the garment in a lower section whose top is at the waist line of the garment and the upper section which is continued below the top side of the lower section to form an apron to cover the upper 25 portion of said lower section in the various relative positions of these garment sections. I also employ an elastic which I assemble with the top edge of the aforesaid lower garment section and which I anchor at its 30 ends at the sides of said lower garment section so that whenever the wearer resumes an upright position the elastic will restore the lower garment section to its proper position.

35 I also desirably provide an opening in one side of the garment that extends from the region of the waist of the garment through the bottom thereof, there being desirably means for buttoning this opening 40 partially shut in order that the garment may retain its normal shape.

I will explain my invention more fully by reference to the accompanying drawings in which Fig. 1 is a perspective view of the 45 preferred form of garment made in accordance with the invention with the opening at the side thereof buttoned partially shut; Fig. 2 is a view illustrating the lower portion of the garment, the opening formation 50 at one side of the garment, and, more clearly the location of the crotch piece; Fig. 3 is a view illustrating the garment in position upon a wearer who is standing upright, this Figure being taken looking toward the front 55 of the garment; Fig. 4 is a view illustrating the garment upon a wearer that has assumed

a stooping posture, this figure being taken from the rear; and Fig. 5 is a view illustrating the garment upon a wearer who has assumed a sitting posture, this view also being taken from the rear.

Like parts are indicated by similar characters of reference throughout the different figures.

The garment illustrated has the general form of a chemise which, in the embodiment of the invention shown, has its top edge 1 at the level of the arm pits, the back and front of the garment being connected at the top of the garment by means of shoulder 60 straps 2, 3 that may be passed over the shoulders of the wearer. A draw string 4 may be threaded through the top of the garment to draw it snugly into place. The garment hangs from the shoulders of the wearer 70 as does a chemise and is constituted a combination garment by the crotch piece 5 that joins the front and back of the garment at the bottom thereof, this crotch piece being midway between the sides of the garment and forming, with the contiguous portions of the garment, openings that receive 75 the legs of the wearer.

For the convenience of the wearer, one side of the garment is formed with an 80 elongated slit or opening 6 therein, this opening extending from the region of the waist of the garment through the bottom thereof to communicate with the adjacent leg opening. The opening 6 may be provided with a button 7 partially to close it. A piece of tape 8 or other binding may be 85 sewed to the garment along the edges of the upper portions of the opening 6 for the purpose of increasing the strength of the 90 material where the button 7 is to be located and the button hole 9 that is to receive the button. This binding also strengthens the bight of the gap 6 at its upper end whereby the cloth may not easily be torn at this 95 place.

If desired the crotch piece 5 may be partially concealed by a small apron 10 attached to the front of the garment.

The back of the garment is formed in a lower section 11 and an upper section 12, these two sections of the garment being separated where these sections are contiguous in order that they may accommodate themselves, without tearing the garment, to stooping and sitting postures of the wearer. Referring to Fig. 4, the upper back section 12

of the garment is pulled away from the lower section when the wearer stoops. When the wearer sits the lower section is strained away somewhat, from the upper section. In either case the separation of the garment at the contiguous portions of the back sections thereof prevents the garment from being injured. In order that the lower back section of the garment may resume its normal position upon the body of the wearer when upright, I provide it with an elastic 13 that is threaded through the hem at the top of the back lower section 11 and is anchored at its ends to the garment at the sides of the lower garment section. This elastic is sufficiently taut to lift the lower garment section whenever the wearer arises from a sitting posture and to hold the bottom section of the garment in snug engagement with the body of the wearer when the stooping posture of Fig. 4 is assumed. In order that there may be no visible gap opened in the back of the garment the top back section 12 of the garment is continued below the lowermost position that may be assumed by the top of the lower section of the garment to form an apron 14 which will overhang the upper portion of the lower section of the garment in all of the positions of the wearer.

The shaping of the back section of the garment may be effected by means of tucks 15.

The entire garment, aside from the shoulder straps, the apron 10, the binding 8, the draw string 4 and the elastic 13 may be made from two pieces of cloth, the front of the garment, the crotch piece 5 and the lower section 11 of the back of the garment

being made from one piece of cloth and the upper section 12 of the back of the garment 40 being made from another piece of cloth.

It will be seen from the drawings of the garment and the description thereof that it is so designed as to avoid binding or cutting anywhere, and that it will be easy upon the 45 wearer in all of her postures. Such a garment is of especial advantage to stout or large women.

Having thus described my invention I claim as new and desire to secure by Letters 50 Patent the following:

A woman's combination undergarment having the general form of a chemise, a crotch piece joining the front and back of the garment at the bottom thereof and defining, in conjunction with adjacent parts of the garment, openings for the legs of the wearer, one side of the garment having an opening therein that extends from the region of the waist of the garment through the 60 bottom thereof, the back of the garment being formed in a lower section whose top is at the waist line of the garment and an upper section which is continued below the top of said lower section to form an apron 65 to cover the upper portion of said lower section in various relative positions of said sections, and an elastic assembled with the top edge of the aforesaid lower garment section and anchored at its ends at the sides of 70 said lower garment section.

In witness whereof, I hereunto subscribe my name this 24th day of January A. D., 1922.

IRENE E. KELLY.
